Primary Examiner — Mary Ann Calabrese*Assistant Examiner* — Sloan Rozin(74) *Attorney, Agent, or Firm* — Ridout & Maybee LLP;
 Mark A. Koch(57) **CLAIM**

The ornamental design for a hanging sign, as shown and described.

DESCRIPTION

FIG. 1 is a front plan view of the first embodiment of the hanging sign.

FIG. 2 is a rear plan view of the first embodiment of the hanging sign.

FIG. 3 is a bottom end view of the first embodiment of the hanging sign.

FIG. 4 is a front plan view of the second embodiment of the hanging sign.

FIG. 5 is a rear plan view of the second embodiment of the hanging sign; and,

FIG. 6 is a bottom end view of the second embodiment of the hanging sign.

The portion shown in broken line depicts unclaimed subject matter that is not part of the claimed design.

1 Claim, 2 Drawing Sheets(56)
